CLAIM

The ornamental Design for a tire sidewall, as shown and described.

DESCRIPTION

FIG. 1 is a perspective view of a tire sidewall showing a design in accordance with the present invention; FIG. 2 is a right side elevational view thereof; and, FIG. 3 is an enlarged front view taken from FIG. 2 thereof. In the drawings, the broken lines showing of the tire tread, inner bead, and the peripheral boundary between the tire tread and the sidewall in FIGS. 1 through 4 depict environmental subject matter and form no part of the claimed design.
